UNITED STATES PATENT OFFICE.

HOMER ALTON PARRISH, OF JACKSON, MICHIGAN, ASSIGNOR TO THE
PARRISH SIGNAL COMPANY, OF SAME PLACE.

ELECTRICAL APPARATUS FOR CONTROLLING SIGNAL OR OTHER CIRCUITS.

SPECIFICATION forming part of Letters Patent No. 663,130, dated December 4, 1900.

Application filed August 11, 1899. Serial No. 726,938. (No model.)

To all whom it may concern:

Be it known that I, HOMER ALTON PARRISH, a citizen of the United States, residing at Jackson, in the county of Jackson and State of Michigan, have invented certain new and useful Improvements in Electrical Apparatus for Controlling Signal or other Circuits, of which the following is a specification, reference being had to the accompanying drawings.

My invention relates to electrical apparatus for controlling the operation of signaling devices.

The embodiment of my invention illustrated and described herein is designed more particularly for operating railway-crossing signals; but such invention is adapted for other uses as well, as will be at once apparent to those skilled in the art. I shall, however, describe the invention as especially adapted for operating crossing-signals.

One of the objects of the invention is to provide electrical devices of the character above indicated which will be adapted to operate for an extended period of time without special attention or the renewal of the batteries, and which, nevertheless, may be relied upon to operate on all occasions.

A further object is to provide a construction which will prevent in a great measure the operation of the signal except in the regular and proper way, one of the principal objections to signals heretofore in use at railway-crossings being that they are subject to manipulation by mischievous persons in such manner as to set or sound the signal when no train is passing, thereby not only giving a false alarm at the crossing, but also wasting the batteries. It is, furthermore, desirable that such signals be arranged so that they are not operated by the passage of a hand-car or railway-velocipede, and this is provided for also by the construction hereinafter described.

To this end my invention consists of an electric signal, such as a bell, the operation of which is controlled through circuits opened and closed by the passage of a car, such circuits being normally open, two of them being ground or metallic circuits and the other a metallic circuit. The former, which may

be termed the "first" and "second" circuits, control the action of the signal-operating devices arranged in the latter or third circuit, it being necessary for the first circuit to be closed before the signal-operating devices in the third circuit can be operated to close the circuit through the bell or signal. The second circuit is provided with an electromagnet or relay which through its armature operates a locking or retaining device for locking out of operative position the device which closes the circuit through the bell or signal, the arrangement being such that when said armature is attracted by said magnet the circuit-closing device is released and may drop, closing the circuit through the bell and giving the alarm. An electric battery is provided in the second circuit which is not strong enough to move the armature connected to the locking device, but is strong enough to energize said magnet sufficiently to enable it to retain the armature in juxtaposition to its poles after they have been moved into such position. The first circuit also contains a magnet or relay the armature of which carries an arm which is adapted to actuate the circuit-closing device of the signaling apparatus, as will be hereinafter described, there being in said first circuit a battery of sufficient power to energize said magnet and cause it to attract its armature whenever the circuit is closed. The batteries of the first and second circuits for convenience of description will be termed the "first" and "second" batteries. In practice the first battery is usually made much stronger than the second; but it should be understood that the relative strength of said batteries to each other is of no moment, it being essential only that the first battery shall be strong enough to effect the operation of the armature of the first-circuit magnet whenever said circuit is closed, while the second battery shall be strong enough only to retain the armature of the second-circuit magnet in juxtaposition to the poles thereof and not strong enough to initially operate said armature. The original operation of the armature of the second-circuit magnet for the purpose of releasing the circuit-closing device is effected by the automatic establishment of the metallic or

third circuit through both batteries and the two magnets, the batteries being connected in series, so that sufficient voltage is secured to energize the second-circuit magnet enough to operate said armature.

The way in which the above-described arrangement of the circuits, batteries, and magnets effects the operation of the signal will be specifically hereinafter pointed out in connection with the drawings. That which I regard as new will be set forth in the claims.

In the drawings, Figure 1 illustrates the application of my invention to a railway crossing, the parts being shown in their normal position. Fig. 2 illustrates the position of the armatures and circuit-closing device when the third circuit only is closed, and Fig. 3 illustrates the arrangement of the armatures and circuit-closing device when the second circuit only is closed and the bell is ringing or the signal is set.

Referring to the drawings, 5 6 indicate the rails of a railway, there being a crossing at or about the point marked C. At or near the crossing C one of the rails, as 5, is provided with an insulated section 7, and at about the distance from the crossing where it is desired to actuate the bell, or set the signal other insulated rail-sections 8 9 are provided, said sections being at about an equal distance from the crossing at opposite sides thereof. Near the rail-sections 8 9 are other insulated rail-sections 10 11, respectively, the sections 8 10 being usually slightly less than the length of a car or locomotive apart, the sections 9 11 being similarly arranged. Near the sections 8 10 the rail 6 is provided with a ground connection 12. A ground connection 13 is also provided near the sections 9 11.

14 indicates the first-circuit electromagnet, and 15 the first battery. The latter is connected to the rail-sections 10 11 by wires 16 17 and to the magnet 14 by a wire 18. 19 indicates the second-circuit electromagnet, and 20 the second battery. The latter is connected to the rail-sections 8 9 by wires 21 22 and to the magnet 19 by a wire 23.

24 indicates a wire connecting the magnets 14 and 19.

25 indicates a wire connecting the wire 24 with the ground.

26 indicates a wire connecting the crossing rail-section 7 with the wire 17 or with the wire 16, if desired.

27 indicates the armature of the first magnet, which is suitably pivoted in proximity to the poles thereof, so that when said magnet is energized said armature will be rocked. The armature 27 is provided with an arm 28, which in the arrangement shown extends upward in proximity to the circuit-closing device or drop 29, pivoted upon a suitable support and arranged to assume either a vertical or an inclined position, as illustrated in the drawings. When in an inclined position, as illustrated in Fig. 3, the drop 29 rests upon a contact-point 30, which is adjustably sup-

ported in a suitable bearing. When in a vertical position, the drop 29 is adapted to be engaged and locked in such position by a latch 31, pivoted upon a suitable pivot 32 and connected to the armature 33 of the second electromagnet, said armature being arranged in a substantially vertical position opposite the poles of the second magnet 19, the arrangement being such that when said armature is attracted by its magnet the latch 31 will be raised, releasing the drop 29, so that it may fall into contact with the contact-point 30. When the electromagnet 19 is not energized, the weight of the latch 31 carries the armature 33 away from its poles, so that the latch returns to operative position. For moving the armature 27 of the first magnet 14 away from the poles of said magnet when the latter is deenergized a spring 34 is provided, as shown. The arrangement of the armature 27 of the first magnet and its arm 28 with reference to the drop 29 is such that when said armature 27 is attracted by its magnet the arm 28 acts to rock the drop 29, carrying it to its vertical position and holding it in position to be engaged by the latch 31.

35 indicates a signal-bell which is located at the crossing. Instead of a bell some other suitable form of electrically-operated signal may be employed.

36 indicates a wire connecting the contact-point 30 with the bell 35.

37 indicates a wire connecting the bell with the wire 17.

38 indicates a wire connecting the wire 18 with the circuit-closing device or drop 29.

The operation of the apparatus is as follows: When a train approaches the crossing C from the right, the wheels first strike the insulated rail-section 10, closing the circuit from said rail-section through the axles and wheels of the train to the rail 6, and thence to the ground, establishing the first circuit, which extends from the ground, as just stated, over wires 16 17 to battery 15, thence over wire 18 to the first-circuit magnet 14, then through said magnet over wire 25 to the ground. The magnet 14 is thereby energized, attracting its armature and carrying the arm 28 into contact with the drop or circuit-closing device 29, which is normally in the position shown in Fig. 1. The signal will not at this time be operated, inasmuch as the bell-circuit is broken between the circuit-closing device or drop 29 and contact-point 30. As soon as the wheels strike the insulated rail-section 8, however, the third or metallic circuit is established, extending from the rail-section 8 by the wheels and axles to rails 6, thence back by the wheels and axles at the other end of the car or locomotive to rail-section 10, thence over wires 16 and 17, through battery 15 and wire 18, to the first magnet 14, thence over wire 24 to the second magnet 19, thence over wire 23 through the second battery 20, and back over wire 21 to rail-section 8. The first and sec-

ond batteries are so set up that when the second circuit, above described, is established the elements come in proper order, connecting said batteries regularly in series. Upon the establishment of the third circuit the first magnet 14 remains energized, while the increased voltage so increases the power of the second magnet that it attracts its armature 33, lifting the latch 31 and releasing the drop 29 or circuit-closing device 29. Said drop, although released by the latch 31, remains in its vertical position, as the arm 28 of the armature 27 holds it in such position. As soon, however, as the train passes beyond the rail-section 10 the third or metallic circuit is broken, deenergizing the first magnet 14, thereby releasing the armature 27, which is carried out or away from the poles of said magnet by the spring 34. This releases the drop 29, which falls into contact with the contact-point 30, closing the bell-circuit and sounding the alarm at the crossing, the bell-circuit being from the bell over wires 37 and 17 to the first battery 15, thence over wires 18 and 38 to the drop 29, thence to contact-point 30, and over wire 36 back to the bell. The latch 31 is at this time held out of operative position by reason of the fact that the second circuit is still closed and the magnet 19 energized, said circuit extending from the ground at 12 to rail 6, thence by the wheels and axles to rail-section 8, thence over wires 21 and 22 through the second battery 20, thence over wire 23 to magnet 19, and thence over wires 24 and 25 to the ground. The current which passes through the second magnet 19 at this time, while insufficient to draw the armature 33 thereto, is sufficient to hold said armature in juxtaposition to said magnet, it having been moved into such position originally by the current supplied by the two batteries in series. As soon as the last wheels pass off from the rail-section 8 the second circuit is broken, deenergizing the magnet 19 and releasing the armature 33, permitting the latch 31 to return to operative position. The bell continues to ring until the train reaches the crossing rail-section 7, when the first circuit is again established from the ground at 12 or 13 over rail 6, through the wheels and axles of the car to rail-section 7, thence over wires 26 and 17 to battery 15, thence over wire 18 to magnet 14, and from said magnet over wires 24 and 25 to the ground, thus energizing said magnet, which attracts its armature 27 and through the arm 28 raises the drop 29, breaking the bell-circuit and stopping the bell, the drop being locked in its vertical position by the latch 31. As the train continues to move to the left when the wheels pass upon rail-section 9 the drop 29 is not released, although the second circuit is again established through the second magnet 19 and battery 20, since, as has been explained, the voltage of said battery or the adjustment of said magnet and its armature is such that the battery 20 alone is not strong enough to energize said magnet

sufficiently to enable it to operate the armature 33 and release the drop 29. When the wheels strike rail-section 11, the third circuit is again established, as already described, and at this time the latch 31 is raised, releasing the drop 29, but said drop does not fall and close the bell-circuit, because the first magnet 14 is also energized and attracts its armature 27, the arm 28 of which holds the drop in its vertical position. As the train passes off of section 9 the first circuit alone is established, so that the second magnet 19 is deenergized, releasing the latch, which at once engages the drop and prevents its falling, when the first magnet 14 is also deenergized. This occurs as soon as the train passes off of section 11. It will thus be seen that the signal is given at the crossing when a train is approaching, which signal is stopped or withdrawn as soon as the train reaches the crossing, and that there is no possibility of the setting of the signal by the train after it has passed the crossing. Furthermore, inasmuch as in order to set the signal it is necessary to electrically connect two insulated rail-sections which are at a considerable distance apart, such signal cannot be operated by the passage of a hand-car, which is shorter than the distance between the two insulated rail-sections, nor can the signal be set by simply connecting either of the rail-sections 8 9 10 11 with the rail 6, so that there is very little danger of the setting of the signal by mischievous persons.

I wish it understood that my invention is not restricted to the specific arrangement or construction of devices shown and described, as various modifications thereof may be made without departing from the essentials of the invention.

That which I claim as my invention, and desire to secure by Letters Patent, is—

1. In a signaling apparatus, the combination of an electrically-operated signal, a circuit-closing device for establishing a circuit which actuates said signal, means normally retaining said circuit-closing device out of operative position, electromagnetic mechanism which controls the operation of said retaining mechanism, means made effective by the passage of a train for supplying a current to said controlling mechanism, means for automatically varying the strength of the current supplied to said controlling mechanism, electromagnetic mechanism for setting said circuit-closing device, and means operated by the passage of the train for actuating said setting mechanism, substantially as described.

2. In a signaling apparatus, the combination of an electrically-operated signal, a circuit-closing device for establishing a circuit which actuates said signal, means normally retaining said circuit-closing device out of operative position, electromagnetic mechanism which controls the operation of said retaining mechanism, a normally open track-

- circuit which includes said controlling mechanism and is adapted to be closed by the passage of the train, means for supplying a current to the circuit which includes said controlling mechanism, electromagnetic mechanism for setting said circuit-closing device, a normally open track-circuit which includes said setting mechanism and is adapted to be closed by the passage of a train, means for supplying a current to the latter circuit, and means for automatically varying the strength of the current supplied to said controlling mechanism, substantially as described.
3. In a signaling apparatus, the combination of an electrically-operated signal, a circuit-closing device for establishing a circuit which actuates said signal, means normally retaining said circuit-closing device out of operative position, electromagnetic mechanism which controls the operation of said locking mechanism, a normally open track-circuit which includes said controlling mechanism and is adapted to be closed by the passage of a train, a battery for partially energizing said controlling mechanism, electromagnetic mechanism for setting said circuit-closing device, a normally open track-circuit which includes said setting mechanism and is adapted to be closed by the passage of a train, a battery in said latter circuit, and means operated by the passage of the train for automatically increasing the current supplied to the controlling mechanism, substantially as described.
4. In a signaling apparatus, the combination of an electrically-operated signal, a circuit-closing device for establishing a circuit which actuates said signal, means normally retaining said circuit-closing device out of operative position, electromagnetic mechanism which controls the operation of said retaining device, a normally open track-circuit which includes said controlling mechanism and is adapted to be closed by the passage of a train, a battery for partially energizing said controlling mechanism, electromagnetic mechanism for setting said circuit-closing device, a normally open track-circuit which includes said setting mechanism and is adapted to be closed by the passage of a train, a battery in said latter circuit, and means operated by the passage of the train for connecting both said batteries in circuit with said controlling mechanisms, substantially as described.
5. In a signaling apparatus, the combination of an electrically-operated signal, a circuit-closing device for establishing a circuit which actuates said signal, means normally retaining said circuit-closing device out of operative position, electromagnetic mechanism which controls the operation of said retaining device, a normally open track-circuit which includes said controlling mechanism and is adapted to be closed by the passage of the train, a battery for partially energizing said controlling mechanism, electromagnetic mechanism for setting said circuit-closing device, a normally open track-circuit which in-

cludes said setting mechanism and is adapted to be closed by the passage of a train, a battery in said latter circuit, and means operated by the passage of the train for connecting both said batteries in series in a metallic circuit including said controlling and setting mechanism, substantially as described.

6. In a signaling apparatus, the combination of an electrically-operated signal, a circuit-closing device for establishing a circuit which actuates said signal, a locking device normally acting to retain said circuit-closing device out of operative position, electromagnetic mechanism which controls the operation of said locking mechanism, a normally open track-circuit which includes said controlling mechanism, electromagnetic mechanism for setting said circuit-closing device, a normally open track-circuit which includes said setting mechanism, and a battery in each of said track-circuits, said circuits being arranged to be closed by the passage of a train, the connections being such that after one of said track-circuits is established, and before the other is closed, a third circuit is automatically established through both batteries and the controlling and setting mechanisms, substantially as described.

7. In a crossing signaling apparatus, the combination of a series of insulated rail-sections, two of said rail-sections being at a considerable distance from the crossing, at each side thereof, and another of said rail-sections being near said crossing, a first track-circuit which is normally open and includes the outermost rail-sections and the rail-section near the crossing, a second circuit including the inner rail-sections at the opposite sides of the crossing, an electrically-operated signal arranged near the crossing, a circuit-closing device for establishing a circuit which actuates said signal, setting mechanism in the first circuit for setting said circuit-closing device, controlling mechanism in said second circuit, retaining devices operated thereby for normally retaining said circuit-closing device out of operative position, means for supplying a weak current to said controlling mechanism when the second circuit alone is closed, means for simultaneously operating said controlling and setting mechanisms, and means for increasing the current supplied to said controlling mechanism when said setting mechanism is operated simultaneously therewith, substantially as described.

8. In a crossing signaling apparatus, the combination of a series of insulated rail-sections, two of said rail-sections being at a considerable distance from the crossing, at each side thereof, and another of said rail-sections being near said crossing, a first track-circuit which is normally open and includes the outermost rail-sections and the rail-section near the crossing, a second circuit including the inner rail-sections at the opposite sides of the crossing, an electrically-operated signal arranged near the crossing, a circuit-closing de-

vice for establishing a circuit which actuates said signal, setting mechanism in the first circuit for setting said circuit-closing device, controlling mechanism in said second circuit, retaining devices operated thereby for normally retaining said circuit-closing device out of operative position, means for supplying a weak current to said controlling mechanism when the second circuit alone is closed, means for supplying a current to said setting mechanism when the first circuit alone is closed, and means operated by the passage of a train for establishing a closed metallic circuit which includes said controlling and setting mechanisms, substantially as described.

9. In a crossing signaling apparatus, the combination of a series of insulated rail-sections, two of said rail-sections being at a considerable distance from the crossing, at each side thereof, and another of said rail-sections being near said crossing, a first track-circuit which is normally open and includes the outermost rail-sections and the rail-section near the crossing, a second circuit including the inner rail-sections at the opposite sides of the crossing, an electrically-operated signal arranged near the crossing, a circuit-closing device for establishing a circuit which actuates said signal, setting mechanism in the first circuit for setting said circuit-closing device, controlling mechanism in said second circuit, retaining devices operated thereby for normally retaining said circuit-closing device out of operative position, a battery in each of said first and second circuits, the battery in said second circuit being insufficient alone to fully energize the controlling mechanism, and means operated by the passage of a train for establishing a third metallic circuit which includes both said batteries in series and the controlling and setting mechanisms, said third circuit being established after the closing of one of said track-circuits and before the other of said track-circuits is closed, substantially as described.

10. In a crossing signaling apparatus, the combination of a series of insulated rail-sections, two of said rail-sections being at a considerable distance from the crossing, in proximity to each other, and another of said rail-sections being near said crossing, a first track-circuit which is normally open and includes the outermost rail-section and the rail-section near the crossing, a second circuit including the intermediate rail-section, an electrically-operated signal arranged near the crossing, a circuit-closing device for establishing a circuit which actuates said signal, setting mechanism in the first circuit for setting said circuit-closing device, controlling mechanism in said second circuit, retaining devices operated thereby for normally retaining said circuit-closing device out of operative position, means for supplying a weak current to said controlling mechanism when the second circuit alone is closed, means for simultaneously operating said controlling and set-

ting mechanisms, and means for increasing the current supplied to said controlling mechanism when said setting mechanism is operated simultaneously therewith, substantially as described.

11. In a crossing signaling apparatus, the combination of a series of insulated rail-sections, two of said rail-sections being arranged along the railway in proximity to each other, at a considerable distance from the crossing, and another of said rail-sections being near said crossing, a first track-circuit which is normally open and includes the outermost rail-section and the rail-section near the crossing, a second circuit including the intermediate rail-section, an electrically-operated signal arranged near the crossing, a circuit-closing device for establishing a circuit which actuates said signal, setting mechanism in the first circuit for setting said circuit-closing device, controlling mechanism in said second circuit, retaining devices operated thereby for normally retaining said circuit-closing device out of operative position, means for supplying a weak current to said controlling mechanism when the second circuit alone is closed, means for supplying a current to said setting mechanism when the first circuit alone is closed, and means operated by the passage of a train for establishing a closed metallic circuit which includes said controlling and setting mechanisms, substantially as described.

12. In a crossing signaling apparatus, the combination of a series of insulated rail-sections, two of said rail-sections being arranged along the railway in proximity to each other, at a considerable distance from the crossing, and another of said rail-sections being near said crossing, a first track-circuit which is normally open and includes the outermost rail-section and the rail-section near the crossing, a second circuit including the intermediate rail-section, an electrically-operated signal arranged near the crossing, a circuit-closing device for establishing a circuit which actuates said signal, setting mechanism in the first circuit for setting said circuit-closing device, controlling mechanism in said second circuit, retaining devices operated thereby for normally retaining said circuit-closing device out of operative position, a battery in each of said first and second circuits, the battery in said second circuit being insufficient alone to fully energize the controlling mechanism, and means operated by the passage of a train for establishing a third metallic circuit which includes both said batteries in series and the controlling and setting mechanisms, said third circuit being established after the closing of one of said track-circuits and before the other of said track-circuits is closed, substantially as described.

13. In a signaling apparatus, the combination of an electrically-operated signal, a signal-circuit therefor, a circuit-closing device

for the signal-circuit, controlling mechanism for operating said circuit-closing device, a plurality of batteries for supplying electricity to said controlling mechanism, the current of one of said batteries alone being insufficient to operate said controlling mechanism to close the signal-circuit, and means operated by the passage of a train for supplying the current from a plurality of said batteries to said controlling mechanism, substantially as described.

14. In a signal apparatus, the combination of an electrically-operated signal, a normally open signal-circuit which includes said sig-

nal, controlling mechanism for closing said signal-circuit, a circuit which includes said controlling mechanism and is closed by the passing of a train, a battery adapted to be placed in circuit with said controlling mechanism and with said signal, and means operated by the passing of a train for automatically placing said battery in circuit with said signal, substantially as described. 15
